FIG. 1.

FIG. 2.

FIG. 3.

UNITED STATES PATENT OFFICE

2,163,626

ELECTRIC SWITCH

Johann G. Peterson, West Hartford, Conn.

Application August 1, 1936, Serial No. 93,873

25 Claims. (CL. 200—154)

My invention relates to electric switches. It has among its objects to provide an improved switch, and further an improved switch of the type described and claimed in my prior Patent No. 1,815,633. Other objects of my invention include the provision of an effective switch of this type which has an improved and simplified construction requiring only a single insulating base member to carry all of the switch mechanism and connections, and which further can be made in a markedly smaller size in such manner as to be particularly adapted for use for heating pads or the like, while at the same time being manufactured at a very substantially smaller cost. Further objects of my invention include the provision of an improved construction and arrangement of combined switch actuating and movable contact mechanism, and an improved operative connection of the same to a manually operable actuating member, as well as the provision of improved cooperating actuating cam and stationary contacts, so that a plurality of circuits may be effectively controlled while utilizing a single base member and having the actuating member on the opposite side of said base member from the contact mechanism. These and other objects and advantages of my improved construction will, however, hereinafter more fully appear.

In the accompanying drawing I have shown for purposes of illustration one embodiment which my invention may assume in practice, the same being illustrated as applied to a through switch particularly adapted to use in electric heating pads.

In the drawing,—

Figure 1 is an enlarged plan of my improved switch mechanism disposed in one casing member, one of the casing members being removed and the other broken away at its lower end to facilitate illustration and the switch being shown in its opposite extreme positions in full and dotted lines;

Fig. 2 is a like view of the opposite side of the switch unit with the latter disposed over the other casing member;

Fig. 3 is a longitudinal section through a portion of the switch and casing, taken on line 3—3 of Fig. 1 but with the switch in the position shown in Fig. 4;

Fig. 4 is a view of the switch unit shown in Fig. 1, wholly removed from the casings, the switch here being indicated in full and dotted lines in its two intermediate positions;

Fig. 5 is a sectional view on line 5—5 of Fig. 4;

Fig. 6 is a view similar to Fig. 4 but with the combined movable cam and contact member lifted off to facilitate illustration, and

Fig. 7 is a detail sectional view on line 7—7 of Fig. 4.

In this illustrative construction, I have shown my invention embodied in a switch in the form of an improved unit, generally indicated at 1, adapted to be enclosed between longitudinally divided through switch casing members 2 and 3, and having an actuating member 4 carrying a finger actuated knob 5 and movable longitudinally of the members 2, 3 into a plurality of operative positions in a slot 6 in the member 2.

Referring more particularly to the improved switch unit, it will be noted that it includes a single base, herein in the form of a single thin flat insulating plate 7 of suitable fiber or composition. This plate herein is adapted to be disposed between like cooperating chambers 8 and 9 in the opposite ends of casing members 2 and 3, herein shown only at the upper ends thereof. The plate 7 also is provided with notches 10 in its ends adapted to cooperate with usual screw-receiving projections 11 on the member 2 adjacent the usual conductor openings 12 in the ends of the latter, which projections 11 and openings 12 are adapted to cooperate in a usual manner with like projections 11' and openings 12' on the other casing member 3, it being understood that like projections 11, 11' and openings 12, 12' are also provided on the opposite ends of the members 2 and 3. In this construction, it will however be observed that shoulders 13 are provided on the projections 11 to support the opposite ends of plate 7 in suitably spaced relation from the bottom of the chamber 8. It will also be noted that the projections 11' on the casing member 3 are so enlarged as to overlie slightly the edges of the notches 10 and thus cooperate with the shoulders 13 and the slot 6 which engages the actuating member 4, in spacing and positioning the unit in the casing.

Upon the plate 7, all the switch mechanism is carried, including its operating mechanism, its contacts, and the switch terminals to which the conductors leading to the line and the heating pad, are led through the end openings 12, 12' in the casing members 2 and 3. Herein, the actuating member 4 has its outer knob carrying end disposed in the plane of the plate 7 and is provided with a bent down portion while its inner end 14 extends along under the bottom of the plate 7 and is pivoted thereto on a suitable pivot, herein in the form of a hollow tubular rivet 15.

extending through the plate 7 at the far side of the longitudinal center line of the plate. Thus, while the actuating portion of the actuating member 4 may be disposed in the plane of the plate 7, the portion 14 may be disposed closely adjacent the bottom of the plate. Further, it will be noted that the bent down portion, herein indicated at 16, moves in a slot 17 provided in the adjacent edge of the plate 7, while the portion 14 is also bent down intermediate its ends, as at 18, in such manner as not to engage the lower end of a pivot member 19 for the movable cam and contact member hereinafter described. This pivot member herein is also in the form of a hollow or tubular rivet, and is located between the pivot 15 and the slot 17 on the opposite side of the longitudinal center line of the plate 7 from the pivot 15. This member 19 herein projects through the plate 7 and above the latter and also has rotatably mounted on the projecting end thereof, my improved combined cam and movable contact member, generally indicated at 20. Further, as shown, a stuck up portion or pin 21 is provided on the portion 14 of the member 4 and extends up through a slot 22 in the plate 7, which is disposed between the pivot 19 and the slot 17, this slot 22 being struck on an arc about the pivot 15 as a center.

Referring more particularly to the combined movable cam and movable contact member 20, it will be noted that the same is actuated by the struck up portion 21 on the actuating member 4 as the bent down portion 16 on the latter moves about the pivot 15 within the limits of the slot 17. As shown, the member 20 is in the form of a plate of conducting material rotatably mounted on the pivot 19 and provided with a laterally extending portion or lug 23, which is in turn provided with an opening or slot 24 somewhat elongated and larger than the projection or pin 21 and adapted to receive the same and permit the desired swinging movement of the member 20. Herein also, the member 20 is normally pressed downward by a spring 25 disposed around the pivot 19 and acting between the plate 20 and a flange portion 26 on the upper end of the rivet 19, in such manner as to press the plate 20 firmly upon an insulating plate 27 which is disposed between the plate 20 and the plate 7. Also the member 20, apart from its laterally extending portion or lug 23, is generally Y-shaped and has this portion 23 extending laterally toward the slot 6 from the base of one of the Y arms. As shown the member 20 is provided with a movable actuating cam portion 28 at one end thereof and with spaced arms or angularly disposed contact portions 29 and 30 at the opposite end thereof, the laterally extending lug 23 being adjacent the base of the arm 30 and between the latter and the cam portion 28. Thus, as the member 4 is moved in either direction about its pivot 15, the member 20 is swung therewith about its pivot 19, the movable cam member 28 moving back and forth in an arc at one side of the pivot 19, while the movable contact members 29 and 30 move back and forth in an arc on the opposite side of the pivot 19, and the bent down portion 14 on the member 4 moves within the limits of the slot 17 as the struck up portion 21 moves within the limits of the arcuate slot 22. Here it will also be noted that the entire member 20 in these oscillating movements rests on the insulating plate 27 and that the latter is also cut away, as at 31, to provide an opening 75 therein exposing the slot 22 throughout the length

thereof and also to provide an extension 32 underlying the contact 30 and the lateral lug 23.

Cooperating with the combined movable cam and contact carrying member 20 are also improved stationary cam and contact members. 5 Herein, a stationary cam 33 is disposed in an arc about the pivot 19 beyond the lower end of the insulating plate 27 (Figs. 1, 4 and 6) and underlying the movable cam member 28. This member 33 as shown is provided with spaced 10 cams or projections 34 spaced by troughs or depressions adapted to receive and position the member 28 and having inclined faces leading from said troughs to the tops of the cams or projections. Thus it will be evident that as the actuating member 4 is swung about its pivot 15, the movable cam member 28 will ride up one face of the adjacent cam projection while compressing the spring 25, and that as soon as the member 28 has passed over the peak of the adjacent cam or projection, the spring will cause the portion 28 to travel rapidly down the other sloping face of the cam into the next adjacent trough, all in such manner as to cause the contact members 29 and 30 to be swung with a snap 25 action about the pivot 19. Further, it will be noted that in the present construction, four troughs being provided, the actuating member 4 and cam 28 and contacts 29 and 30 have four operative positions between which they are moved 30 with a snap action.

Also, it will be noted that in one of these positions, indicated in dotted lines in Figure 1, both of the contacts 29 and 30 will be in an open circuit position with both of these movable contacts still supported on the insulating plate 27. When, however, the actuating member is moved up from the dotted line position shown in Figure 1 to the dotted line position shown in Figure 4, the contact 29 is moved on to a narrow stationary contact 35 of substantially the same width as the contact 29, while the contact 30 still remains over a portion of the insulating plate 27, the movable cam 28 then being in the second trough or position from the left shown in dotted 45 lines in Figure 4. As the actuating member 4 is moved further upward to the full line position shown in Figure 4, the contact 29 moves off of the contact 35 and into engagement with a substantially wider stationary contact 36, the contact 29 engaging the adjacent corner of this stationary contact 36 in this position, i. e. when the movable cam 28 is in the third trough from the left, as shown in full lines in Figure 4. Upon moving the actuating member 4 to its extreme 55 up position, shown in full lines in Figure 1, the contact member 28 then is moved over the wide stationary contact 26 to the far side of the latter while still remaining in contact therewith, while the other movable contact 30 moves into engagement with the stationary contact 35, the movable cam member 28 then being in the fourth trough from the left, as shown in full lines in Figure 1. Here attention is also directed to the fact that both of the stationary contacts 35 and 36 are disposed in the plane of the insulating plate 27 in such manner that the movable contacts 29 and 30 move freely on to and off of these stationary contacts 35, 36 while being supported in all other positions by the insulating plate. 70

In my improved construction, not only the cam member 33 but the contacts 35 and 36 are formed integral with switch terminal members herein indicated at 37, 38 and 39, respectively, and suitably connected to the same side of the plate 7 75

by rivets 40, while usual binding screws 41, 42 and 43 are carried on these plates 37, 38 and 39, respectively. Attention is further directed to the fact that on the opposite side of the plate 1 a through connection is provided in the form of a strip 44 suitably attached to the insulating plate 1, as by a rivet 45, and carrying binding screws 46 and 47 at its opposite ends, one of which is herein adjacent one end of the plate 1, while the other is adjacent the pivot 15; the plate 44, however, being spaced from this pivot and also from the rivet 40 attaching the terminal plate 39.

In the use of my improved construction, it will be evident that when the several binding screws 15 are suitably connected to the line and a heating pad in the usual manner, the actuating member 5 may be readily operated to change the circuit connections as desired, by moving the actuating knob 5 reversely longitudinally within the limits 20 of the slot 6 in the casing 2 in a usual manner. Thus, it is possible to obtain the desired "off", "low", "medium" and "high" heat positions of the switch, of which the "off" position is illustrated in dotted lines in Figure 1, the "low" position in dotted lines in Figure 4, the "medium" position in full lines in Figure 4, and the "high" position in full lines in Figure 1. Further, it will be evident that in moving from any of these 25 positions to the next adjacent position, irrespective of the direction of movement of the knob 5, the movable contact member 20 will be moved with a snap action in such manner as to cause the contacts 29 and 30 to move therewith and thus minimize arcing at the contacts. Also it 30 will be noted that in each position the parts will be held definitely in that position through the engagement of the movable cam 28 with the walls of the trough in which it is then located.

As a result of my improved construction, it is 40 made possible to provide only a single insulating plate 1, as distinguished from the plurality of such plates as shown in my prior patented construction. Further, it is made possible to provide a single combined movable cam and movable 45 contact member, as distinguished from the plurality of such members shown in my previous construction. It is further made possible to dispose both the movable cam and movable contacts on the same face of the single insulating plate, and 50 also to dispose the stationary cam and stationary contacts on this same face, while having the movable actuating member disposed on the opposite face of the insulating plate and operatively connected to the movable cam and movable contact member in such manner as to effect the desired 55 movement of the parts with the snap action described. Attention is further directed to the fact that my improved construction is thus not only markedly more compact than my prior construction, but especially adapted to use in a very small 60 outer casing, especially convenient for use as a through switch in the conductors leading to an electric heating pad. It will also be observed that my improved construction is one which enables 65 the manufacturing cost of the switch to be very substantially reduced as compared with my prior patented construction, while at the same time the construction is also adapted to be very readily and inexpensively assembled due to the minimum number of parts employed, all while continuing to produce a switch which very satisfactorily controls the circuit connections. Here attention is also directed to the fact that in this 70 construction the spring 25 not only helps to 75 throw the movable contacts 29 and 30, but also

helps to press the latter down in all positions of the same, while the insulating plate 27 provides a support for these movable contacts when they are not in engagement with the stationary contacts 35, 36, and further acts to assure that the 5 movable contacts will move freely off of and on to the stationary contacts while preventing tipping of the member 20. Other advantages of my improved construction will, moreover, be clearly apparent to those skilled in the art.

While I have in this application specifically described one form which my invention may assume in practice it will be understood that this form of the same is shown for illustrative purposes and that the same may be embodied in the 15 above and other modified forms without departing from its spirit or the scope of the appended claims.

What I claim as new and desire to secure by Letters Patent is:

1. In an electric switch, a base, stationary contact means thereon, pivoted actuating and movable contact members thereon disposed on opposite outer faces thereof, the actuating member being operable from one edge of said base and the movable contact pivot being between said edge and the pivot of the actuating member, and operative connections between said actuating member and movable contact member including actuating means on the face carrying said contact member and actuated upon movement of said actuating member for throwing the movable contact with a snap action.

2. In an electric switch, a base, stationary contact means thereon, pivoted actuating and movable contact members thereon disposed on opposite outer faces thereof, the actuating member being operable from one edge of said base and the movable contact pivot being between said edge and the pivot of the actuating member, and operative connections actuated upon movement of said actuating member for throwing the movable contact with a snap action including stationary and movable cam means on the same face of said base as said movable contact member and on the opposite side of said movable contact pivot from said stationary contact means.

3. In an electric switch, a base, stationary contact means thereon, pivoted actuating and movable contact members thereon disposed on opposite faces thereof, the actuating member being operable from one edge of said base and the movable contact pivot being between said edge and the pivot of the actuating member, and operative connections actuated upon movement of said actuating member for throwing the movable contact with a snap action including cooperating cam means on the same side of said base as said movable contact member and having one element movable with said movable contact member and cooperating spring means maintaining the latter and said movable cam element under tension and also on the same side of said base therewith.

4. In an electric switch, a base, stationary contact means thereon, pivoted actuating and movable contact members pivoted on said base on different axes differently spaced from an edge of said base and disposed on opposite faces thereof, an operative connection between said members disposed between the nearest axis and the free 70 end of said actuating member, and snap actuating means for said movable contact member operative upon movement of said operative connection.

5. In an electric switch, a base having an arcu-

ate cut away portion therein, pivoted actuating and movable contact members thereon and disposed on opposite outer faces of said base including an actuating member projecting under 5 said cut-away portion beyond an edge of said base on the remote side of said cut-away portion from the pivot of said actuating member, an operative connection between said members having actuating means movable in said cut away portion, and snap actuating means for said movable contact member operative upon movement of said operative connection.

6. In an electric switch, a base, stationary contact means thereon, pivoted actuating and movable contact members disposed on opposite faces thereof pivoted thereon on laterally spaced pivots with the movable contact pivot nearer an edge of the base and the actuating member projecting beyond said edge, an operative connection between said members disposed between the pivot of said contact member and the free end of said actuating member, and snap actuating means for said movable contact member on the same face of said base carrying said movable contact member and operative upon movement of said operative connection.

7. In an electric switch, a base, stationary contact means thereon, pivoted actuating and movable contact members disposed on opposite outer faces thereof and pivoted on opposite sides of the longitudinal center line of said base, an operative connection between said members disposed between the pivot and the free end of said actuating member, and snap actuating means for 30 said movable contact member on the same face of said base carrying said movable contact member and operative upon movement of said operative connection.

8. In an electric switch, a base having a cut 40 away portion therein, an actuating member pivoted on said base and disposed on one face thereof and having an actuating portion between the pivot of said actuating member and the free end thereof and movable in said cut away portion, a movable contact member disposed on the opposite face of said base from said actuating member and actuated by said portion, and snap actuating means acting on said movable contact member and actuating the same upon movement of said 50 member about its pivot.

9. In an electric switch, a base, a swingable actuating member pivoted on one face of said base and operable from one edge thereof, switch mechanism disposed on the opposite face of said base, including a swingable contact member and 55 cooperating stationary contacts and movable and stationary cam means for effecting snap action movement of said swingable contact member, a portion of said swingable contact member and said actuating member being swingable through similar overlying paths, and an operative connection directly between said actuating member and said swingable contact member and clearing said base for manually actuating said switch mechanism.

10. In an electric switch, a base, a swingable actuating member pivoted on one face of said base and operable from one edge thereof, switch mechanism disposed on the opposite face of said base, including a swingable contact member and 70 cooperating stationary contacts and movable and stationary cam means for effecting a snap action movement of said swingable contact member, a portion of said swingable contact member and 75 said actuating member being swingable through

substantially corresponding and overlying paths, and a pin and slot connection directly between said actuating member and said swingable contact member and clearing said base for manually actuating said switch mechanism.

11. In an electric switch, a base, an insulating plate thereon, spaced stationary contacts flush with said insulating plate at one edge thereof, a movable contact member pivoted on said base having cooperating spaced contacts movable progressively over said insulating plate and said first mentioned contacts, an actuating member on the opposite face of said base from said insulating plate, and means operable upon movement of said actuating member for moving said 15 movable contact member with a snap action including cam means disposed on the opposite side of the pivot of said movable contact member from said stationary contacts and at the opposite edge of said insulating plate from said stationary contacts.

12. In an electric switch, a base, spaced contacts thereon, a movable contact member pivoted on said base having cooperating spaced contacts movable over said first mentioned contacts, an 25 actuating member on the opposite face of said base from said movable contact member and having operative connections for actuating said movable contact member, and means operable upon movement of said movable contact member for 30 moving said movable contact member with a snap action including stationary cam means disposed along the opposite side of the pivot of said movable contact member from said first mentioned contacts and a cooperating movable cam movable with said movable contact member.

13. In an electric switch, a base, an insulating member thereon, spaced contacts flush with said insulating member, a movable contact member pivoted on said base having cooperating spaced 40 contacts movable over said insulating member and said first mentioned contacts, an actuating member on the opposite side of said base from said insulating member having operative connections for actuating said movable contact member, 45 and means operable upon movement of said movable contact member for moving said movable contact member with a snap action including stationary cam means disposed along the opposite edge of said insulating member from said first 50 mentioned contacts, a cooperating movable cam movable with said movable contact member, and spring means coaxial with the pivot of said movable contact member and acting on the latter.

14. In an electric switch, a base, pivoted actuating and movable contact members thereon and disposed on opposite faces thereof, said movable contact member being substantially Y-shaped and having movable contacts and an actuating cam on opposite ends thereof and a lateral extension, an operative connection between said lateral extension and said actuating member, cam means cooperating with said actuating cam to throw said movable contact member quickly, and stationary contact means cooperating with the movable contacts on said movable contact member.

15. In an electric switch, a base, pivoted actuating and movable contact members thereon and disposed on opposite faces thereof, said movable contact member having movable contacts and an 70 actuating cam on opposite ends thereof and a lateral extension, an operative connection between said lateral extension and said actuating member, cam means cooperating with said actuating cam to move said movable contact member 75

5 quickly, stationary contact means cooperating with the movable contacts on said movable contact member, and spring means disposed coaxially of the pivot of said movable contact member and acting on the latter.

10 16. In an electric switch, a base, pivoted actuating and movable contact members thereon and disposed on opposite faces thereof, said movable contact member having movable contacts and an actuating cam on opposite ends thereof and a lateral extension, an operative connection between said lateral extension and said actuating member, cooperating cam means and stationary contacts cooperating with the cam means and movable contacts on said movable contact member, and spring means disposed coaxially of the pivot of said movable contact member and acting thereon, said actuating member being pivoted on the opposite side of the pivot of said movable contact member from the free end of said actuating member and said operative connection being between the pivot of the movable contact member and the free end of said actuating member.

25 17. In an electric switch, a base, pivoted actuating and movable contact members thereon and disposed on opposite faces thereof, said movable contact member having movable contacts and an actuating cam on opposite ends thereof and a lateral extension, an operative connection between said lateral extension and said actuating member, and cooperating cam means and stationary contacts cooperating with the cam means and movable contacts on said movable contact member, said actuating member having an operating portion substantially in the plane of said base and a bent down portion underlying said base, and said operative connection including a projecting portion carried on said bent down portion and extending through an aperture in said base into said lateral extension.

30 18. In an electric switch, a base, stationary contact means thereon, pivoted actuating and movable contact members pivoted thereon and spaced laterally from one side edge of said base and having said actuating member projecting beyond said edge, said movable contact member and stationary contact means being between the pivots of said actuating and movable contact members and one end of said base, operative connections between said members for moving said movable contact member upon movement of said actuating member, and means for throwing said movable contact member when so moved with a quick movement, including cam means disposed between said pivots and the opposite end of said base.

35 19. In an electric switch, a base, stationary contact means thereon, pivoted actuating and movable contact members pivoted thereon on pivots spaced laterally from one side edge of said base and having said actuating member projecting beyond said edge, the pivot of the actuating member being on the side of the pivot of the movable contact member remote from said edge of the base, operative connections between said members for moving said movable contact member upon movement of said actuating member, and means for throwing said movable contact member when so moved with a quick movement, including cam means disposed between said pivots and one end of said base, said operative connections including means for permitting relative movement between said members and being disposed between the pivot of the movable contact

tact member and the free end of said actuating member.

40 20. In an electric switch, a base, pivoted actuating and movable contact members pivoted thereon on pivots spaced laterally from one side of said base, the pivot of the actuating member being on the side of the pivot of the movable contact member remote from said edge of the base, operative connections between said members for moving said movable contact member upon movement of said actuating member, means for throwing said movable contact member when so moved with a quick movement, including cam means disposed between said pivots and one end of said base, and stationary and movable contact means on the opposite end of said base and on the opposite side of said operative connections from said cam means.

45 21. In an electric switch, a base plate, a pivoted actuating member thereon disposed on one face thereof, switch mechanism including stationary and movable contacts and actuating mechanism for the latter disposed on the opposite face of said plate and actuated upon movement of said actuating member, switch terminals on the same face of said plate as said switch mechanism, a through connection on the same face of said plate as said actuating member, and a through switch casing enclosing said base plate and having means for enabling operation of said actuating member from the exterior of said casing.

50 22. In a through switch, cooperating enclosing casing members presenting a chamber therebetween, a switch unit in said chamber having a base and switch mechanism thereon and an operating member for said mechanism operable from the exterior of said chamber, and cooperating means inside said chamber and on said casing members for clamping the opposite ends of said base therebetween.

55 23. In a through switch, cooperating enclosing casing members presenting a chamber therebetween, a switch unit in said chamber having a base and switch mechanism thereon and an operating member for said mechanism operable from the exterior of said casing members, and cooperating means inside said chamber and on said casing members for clamping the opposite ends of said base therebetween, said switch mechanism being carried on one face of said base and said operating member on the opposite face thereof and both said mechanism and operating member being spaced from the adjacent inner faces of said chamber by said cooperating clamping means.

60 24. In a through switch, cooperating enclosing casing members presenting a chamber therebetween and having projections on one of said members having shoulders thereon and cooperating projections on the other member, and a switch unit in said chamber and positioned by said projections having a base located by said first mentioned projections and supported on said shoulders and engaged by said cooperating projections, said switch unit having switch mechanism thereon and an operating member operable from the exterior of said casing members.

65 25. In a through switch, cooperating enclosing casing members having end conductor apertures and presenting a switch unit chamber therebetween and also having a longitudinal slot communicating with said chamber and within said chamber projections on one of said members having shoulders thereon and cooperating projec-

70 75

5 tions on the other member, and a switch unit in said chamber and positioned by said projections having a base located by said first mentioned projections and supported on said shoulders and engaged by said cooperating projections, said switch unit being spaced from the walls of said chamber by said projections and having a switch

mechanism on one face of said base spaced from the adjacent wall of said chamber and an operating member on the opposite face of said base also spaced from the adjacent wall of said chamber and extending through said slot. 5

JOHANN G. PETERSON.
